WEATHERBOARDING

Lester Kirschbraun, Leonia, N. J., assignor to
 The Patent and Licensing Corporation, Boston,
 Mass., a corporation of Massachusetts

Application June 11, 1931, Serial No. 543,536

5 Claims. (Cl. 20—5)

This invention relates to constructional material adapted to be employed in covering and weatherproofing the outer surfaces of a building and particularly the side walls thereof, and is 5 further directed to a new method of producing the same.

More specifically the invention relates to constructional units adapted to be employed as a 10 weatherproof covering that closely simulates a brick wall.

Heretofore, for this purpose it has been proposed to employ laminated units, each unit consisting of a wooden strip having narrow spaced strips of roofing material adhesively secured 15 thereto. These strips are expensive to manufacture because the proper spacing and cementing of the narrow strips to the base is a time consuming and tedious task. Moreover, when strips 20 of this nature are laid on the side walls of a building, the structure is subject, under the action of the weather, to the tendency towards delamination.

Accordingly, an object of my invention is to 25 provide inexpensive, weatherproof, constructional units which when laid on the side walls of a building, afford adequate weather protection and closely simulate a brick, stone or other like wall, and are not subject to delamination when exposed to the weather.

30 Another object of my invention resides in the novel manner of procedure for manufacturing the constructional units.

In the accompanying drawing:

Figure 1 is a plan view of a constructional unit 35 embodying my invention;

Figure 2 is a front elevation of a portion of a wall covering closely simulating a brick wall and comprising a plurality of my novel units illustrated in Figure 1;

40 Figure 3 is a sectional view taken on line 3—3 of Figure 2;

Figure 4 is a sectional view taken on line 4—4 of Figure 2.

45 Figure 5 is a transverse section of one of the units taken along line 5—5 of Figure 1;

Figure 6 is a similar view taken along line 6—6 of Figure 2; and

50 Figure 7 is a similar view taken along line 7—7 of Figure 2.

In accordance with my invention, the constructional units may consist of unitary structures of moulded or compressed pulp such as wood pulp, 55 can pulp or other suitable material or a thermoplastic fibrous composition board made on a paper machine from suitable mixtures of fibre

and aqueous dispersions of a waterproof thermoplastic substance.

An embodiment of my invention consists in the use of a water-resistant material having thermoplastic properties, such as that made on a paper making machine from a suitable mixture of fibrous material and aqueous dispersion of asphalt. Material of this character in which the waterproof thermoplastic ingredient is incorporated with the fibre before formation into sheets 10 or boards is readily susceptible to shaping as by moulding or embossing operations. According to my invention, the thermoplastic sheet or board is preferably embossed by any suitable means such as between male and female dies of appropriate 15 contours to provide the units hereinafter described and shown in Figures 1 and 5. As shown the constructional unit or strip is of general rectangular shape with upper and lower edges 41 and 42 respectively and side edges 43 and 44. The 20 strip is provided with raised substantially rectangular areas 45 bordered along their upper edges by a horizontal depression 46, the upper extremity of which is spaced from the edge 41 a distance equal to the desired horizontal lap and 25 the lower extremity of which is spaced from the edge 42 a distance corresponding to the height of a common brick. The raised areas 45 are bounded along their lateral ends by parallel, transverse depressions 47, spaced from each other a distance 30 corresponding to the length of a common brick.

The lateral ends of the strips are formed with depressions 48 and 49 of substantially the same depth as that of the depressions 47 and of a width, 35 respectively, of about one-half and three times the width of said depressions 47. These end depressions are so proportioned that the units, finished as hereinafter described, may be laid in courses with sufficient side lap between adjacent 40 strips while preserving the simulation of brick wall construction.

In order that the finished strips may be laid in overlapping courses with the bottom face of each strip lying closely adjacent the top face of the 45 subjacent course, I provide that portion of the strip between the longitudinal depression 46 and the upper edge 41, with raised portions 50 and transversely extending parallel depressions 51 and 52 of approximately the same depth as the 50 depressions and raised portions on the exposed area of the strip. All of the depressions 51 are of the same or slightly greater width than the depressions 47, and are located in such position that the vertical center lines thereof lie midway 55

between the vertical center lines of the depressions 47. The depression 52 is of the same or slightly greater width than the depression 48, and is located a predetermined distance from one of the lateral ends of the strip to provide the proper amount of lap between adjacent shingles.

According to my invention the rectangular areas of the thermoplastic unitary strips are provided with a coating of weatherproof material 10 in which is partially embedded granules of a color resembling that of the usual varieties of brick and contrasting with that of the recesses or depressions of said strip, to present brick simulations standing out in relief beyond the mortar 15 joint simulations afforded by the recesses or depressions.

Constructional units of this character may be produced in accordance with my invention by following the steps to be presently outlined.

20 Whatever the composition of the base, it may be coated over its entire area, or on the portions to be exposed, or only on the exposed face of the raised or relief areas, with a suitable weatherproof material such as a high melt point asphalt 25 or similar bitumen. This coating operation may be accomplished in any suitable manner, such as by dipping the strips in a bath of the coating material or by spraying, doctoring or otherwise applying the coating material to the desired portions or areas of the strip.

Thereafter and while the coating on the face to be exposed is still tacky, the surfacing material is applied thereto in such a way as to cover only the rectangular relief areas. This may be 30 accomplished, for example, by placing the coated faces of the strips in contact with a bed of granules, such as comminuted slate, slag or the like, of suitable brick color. Where coating material is applied to the grooves or depressions as well as to the relief or raised areas, care should be 35 exercised in the surfacing operation to preclude the brick or other light colored granules from adhering to the coating in the grooves or depressions and thus impair the mortar effect intended to be provided by the depressions. To 40 this end, the depth of the bed and the size of the granules in this operation should preferably be so related to the depth of the grooves or depressions in the strip that when the coated face of 45 the strip is brought into contact with the granules, the latter will be picked up by and adhere only to the areas in relief, leaving the depressions or grooves unsurfaced and of a dark or black color. If desired, however, where the coating material has been applied also to the grooves or 50 depressions, the latter may be surfaced with black or other colored granules contrasting with that of the granules on the rectangular relief areas and of a size preferably finer than said last mentioned granules. This surfacing may readily be 55

accomplished by pressing the partially surfaced face into a sufficiently deep bed of fine black granules to permit the latter to be picked up by the adhesive or tacky coating in the grooves or depressions.

I claim as my invention:

1. A constructional unit comprising a thermoplastic unitary substantially rigid fibrous base, said base being embossed to provide a plurality of rows of depressions and raised areas and 10 said rows being spaced from each other by a depression extending horizontally throughout the length of the unit, each of said rows including a plurality of transverse depressions and one of the depressions of one of said rows being wider than 15 the other depressions of said row.

2. A constructional unit comprising a thermoplastic unitary substantially rigid fibrous base, said base being embossed to provide a plurality of rows of depressions and raised areas and said 20 rows being spaced from each other by a depression extending horizontally throughout the length of the unit, each of said rows including a plurality of transverse depressions, the depressions of the upper of said rows being slightly wider than 25 the corresponding depressions of the lower row.

3. A constructional unit comprising a thermoplastic unitary substantially rigid fibrous base said base being embossed to provide a plurality of rows of depressions and raised areas and said 30 rows being spaced from each other by a depression extending horizontally throughout the length of the unit, each of said rows including a plurality of transverse depressions, the raised areas and depressions of the lower of said rows being 35 of substantially greater dimension transversely of the unit than are the raised areas and depressions of the upper of said rows.

4. An article of manufacture comprising a composition board for use as a building covering unit, said board having a layer of asphaltum applied to a surface thereof, a coating of grits pressed into said asphaltum and a plurality of depressions pressed into said surface to effect an uneven appearance thereto, said depressions 45 having differently colored grits pressed therein.

5. An article of manufacture comprising a composition board for use as a building covering unit, said board having a layer of asphaltum applied to a surface thereof, a coating of grits 50 pressed into said asphaltum and a plurality of depressions pressed into said surface to define a plurality of rows of depressions and raised areas, said rows being spaced from each other by a depression extending horizontally throughout 55 the length of the board, each of said rows including a plurality of transverse depressions, said depressions having differently colored grits pressed thereinto.
